To all whom it may concern:

Be it known that I, PAUL C. DELAIZE, a citizen of France, residing in New York, in the county and State of New York, have invented a new, original, and ornamental Design for Bottle, of which the following is a specification, reference being had to the accompanying drawing, forming part thereof.

Figure 1 is a top plan view of a bottle showing my new design;

Figure 4 is a reduced perspective view.

The essential feature of the design resides in the neck and stopper.

I claim:
